SHOE BOTTOM UNIT AND METHOD OF
MAKING THE SAME

John M. Whelton, Peabody, Mass., assignor to
United Shoe Machinery Corporation, Paterson,
N. J., a corporation of New Jersey

Original application March 24, 1932, Serial No.
600,921. Divided and this application May 8,
1936, Serial No. 78,690

16 Claims. (Cl. 12—146)

This invention relates to improvements in shoe bottom units and to improvements in methods of making shoe bottom units. The present invention is a division of my earlier application, Serial No. 600,921, filed March 24, 1932, upon which United States Letters Patent No. 2,065,463 was granted December 22, 1936.

It is a common practice to stiffen the shank portions of shoe bottoms by the use of narrow stiffener strips such as the usual metallic shank stiffeners and it is also customary to reinforce the shank portions of insoles by securing thereto by means of adhesive or otherwise a reinforcing piece of leather, fiber or similar material. In order more effectively to reinforce the shank portions of shoes and to facilitate the operations of lasting the upper and laying the outsole so as accurately to reproduce the lines of the last in the shank portions of the shoes, the present invention provides a shoe bottom unit comprising separate reinforcing and stiffening members and having novel provision for maintaining the members in assembled relation. The bottom unit herein shown comprises an insole, a heel and shank reinforcing piece, and a shank stiffener, the insole and the reinforcing piece being secured together by means of cement with the greater part of the shank stiffener interposed between them, the shank stiffener being located widthwise with respect to the other parts and being positively maintained against transverse displacement by having its opposite end portions extending through apertures formed either in the reinforcing piece or in the insole. The heel and shank reinforcing piece may be secured to the lower or lasting side of the insole, in which case the shank stiffener receiving apertures will be formed in the reinforcing piece; or it may be secured to the upper side of the insole, in which case the apertures will be formed in the insole.

As illustrated, the invention also provides a shoe bottom unit adapted for assembly with an insole and comprising separate reinforcing and stiffening members such as a heel and shank reinforcing piece and a metallic shank stiffener strip, the reinforcing piece being apertured to receive the opposite end portions of the stiffener strip.

Considered in another aspect the invention also provides an improvement in methods of making reinforced insoles which consists in cutting out an insole, forming a reinforcing member for the shank portion of the insole, forming in one of said parts two apertures spaced lengthwise thereof, inserting the opposite end portions of a shank stiffener in said apertures, molding the

insole and the reinforcing piece to impart thereto longitudinal and transverse curvatures corresponding to the longitudinal and transverse curvatures of the bottom of a last, and securing the insole and reinforcing piece together with the body portion of the shank stiffener interposed between them.

In the use of an insole unit made in accordance with this method and embodying the features of construction hereinbefore referred to the unit is tacked or otherwise secured to a last, an upper is cemented on the last and its margins secured preferably by cement in overlusted relation to the insole unit, after which an outsole is laid and secured, for example, by means of cement to the overlusted margins of the upper. The apertures in the insole or in the reinforcing unit provide convenient and effective means for maintaining the shank stiffener in assembled relation to the other parts, with the greater part of the shank stiffener interposed between those parts leaving no substantial amount of metal exposed at the lower or lasting side of the unit to interfere with the operation of lasting the upper margins or with the formation of a satisfactory bond between the insole unit and the upper margins or between the upper margins and the outsole, such an arrangement being particularly advantageous in the manufacture of shoes the soles of which have exceptionally narrow shank portions.

The invention will now be explained with reference to the accompanying drawing, in which

Figs. 1 and 2 are perspective views of an insole and a heel and shank reinforcing piece, respectively, used in the manufacture of my improved reinforced insole showing the parts as they appear after having been coated with adhesive for use in securing them together;

forced insole of modified construction showing, respectively, the upper and lower sides of the insole; and

Fig. 13 is a sectional view taken along the line 5 XIII—XIII of Fig. 12.

Referring to the drawing, the improved shoe bottom unit or reinforced insole 30, best shown in Figs. 8 and 9, comprises an insole proper 32, a heel and shank reinforcing piece 34, and a 10 metallic shank stiffener 36. The insole 32 may be made of leather or any suitable flexible insole material, while the reinforcing piece 34 is composed of relatively stiff moldable material, such as leather, fiber or leatherboard. Both the 15 insole 32 and the reinforcing piece 34 may be cut to shape in any customary manner, for example, they may be died out or they may be cut by a rounding operation. Preferably, the reinforcing piece 34 is cut to correspond in outline 20 to that of the heel and shank portion of the insole. The shank stiffener 36 consists of a narrow strip of resilient metal which is initially curved longitudinally to correspond to the longitudinal curvature of the bottom of the last to 25 be used in making the shoe in which the insole unit is to be incorporated. As shown, the front end portion of the reinforcing member 34 is skived or beveled to provide a thin forward edge which will not have any tendency to produce an 30 undesirable ridge in the outsole of the shoe.

In order to provide for maintaining the shank stiffener 36 in assembled relation with the reinforcing piece 34 and to facilitate attachment of the shank stiffener to the insole two openings of 35 substantial width herein shown as circular apertures 50 are formed in the reinforcing piece for receiving the opposite ends of the shank stiffener.

Prior to the assembly of the shank stiffener with the reinforcing piece both the reinforcing piece and the insole are coated with adhesive, 40 for example, rubber latex, and allowed to set long enough to render the adhesive in proper condition for securing the parts together. As indicated in Figs. 1 and 2, the adhesive will be applied to the entire surface at one side of the 45 reinforcing piece and to a corresponding portion of the surface at one side of the insole, the adhesive coating upon the insole being indicated at 66 and that upon the reinforcing piece at 68.

Before the reinforcing piece and the insole are 50 assembled the opposite end portions of the shank stiffener 36 are inserted through the apertures 50 in the reinforcing piece and the shank stiffener is adjusted longitudinally to bring its forward end into a desired predetermined relation to, herein illustrated as substantially flush with, the forward edge 44 of the reinforcing piece. The insertion of the longitudinally curved shank stiffener through the circular apertures 50 is effected without distorting to any substantial 55 extent the adjacent material of the reinforcing piece or member 34 and imparts a longitudinal curvature to the reinforcing piece which approximates that of the shank stiffener, as indicated in Figs. 4, 5 and 6. As shown, the shank 60 stiffener has struck up at its rear end a single pointed spur or prong 70 which, during the molding of the reinforcing piece and the insole, is pressed into and becomes embedded within the material of the reinforcing piece and thus functions 65 positively to hold the shank stiffener against longitudinal displacement. Moreover, the pressure of the pointed tip of the spur 70 against the reinforcing piece serves to prevent accidental endwise displacement of the shank 70 stiffener relatively to the reinforcing piece be-

fore the molding operation takes place. It will thus be seen that after the end portions of the shank stiffener have been threaded through the apertures in the reinforcing piece there has been produced, as a step product of my method, a 5 shank stiffener unit consisting of the reinforcing piece 34 and the shank stiffener 36.

The shank stiffener unit just described is now ready to be adhesively secured to the insole and, as herein illustrated, this operation is performed 10 by molding pressure which serves also to mold the shank portions of the insole and the reinforcing piece so as to curve them both longitudinally and transversely to correspond to the longitudinal and transverse curvatures of the bottom of the last. The molding and attaching operations are performed, as herein illustrated in Fig. 7, by the cooperation of a rigid form 74 with a yieldable pad 76, the upper or work engaging surface of the form being curved both lengthwise and crosswise to accomplish the desired 15 molding. Advantageously the form 74 and the pad 76 may be incorporated in a molding machine, such as that disclosed in my copending application, Serial No. 701,814, filed December 25 11, 1933, upon which United States Letters Patent No. 2,065,465 was granted December 22, 1936. In the molding machine above referred to the insole and the reinforcing piece are assembled 20 with their edges in alignment and both these 25 parts are properly positioned with respect to the form 74 by means of suitable gaging devices, the construction and operation of which is fully disclosed in the copending application just referred to. In the operation of the molding machine 30 the pad 76 is caused to descend and apply pressure to the work and thereby to secure the insole and the reinforcing member together as well as to mold them to the contour of the form.

Upon release of the molding pressure the reinforced insole is removed from the molding machine. Preferably the opposite lateral edges along the shank portion of the insole are reduced by any suitable means (not herein shown) so as to provide the beveled surfaces 45 indicated at 180 in Fig. 9, the angle of bevel being such as to blend with the profile of the last.

In Figs. 11, 12 and 13 there is shown a modified reinforced insole construction in which a heel and shank reinforcing piece 340 is applied to the upper or grain side of an insole 320 so that instead of being located between the inner and outer soles of the finished shoe it will be located at the upper or inner side of the insole where in the absence of a sock lining it will be directly engaged by the foot of the wearer. In an insole unit of this type it is convenient to form the shank stiffener receiving apertures in the insole itself, as indicated at 500, instead of in the reinforcing member. The opposite end portions of the shank stiffener 360 will, in this instance, be threaded through the apertures 500 in the insole, thus causing the main or body portion of the shank stiffener to be located between the insole and the reinforcing piece as in the form of insole hereinbefore described. By constructing an insole unit with the heel and shank reinforcing piece applied to its upper side as just described it is practicable to channel the insole upon its lower or lasting side so as to provide for the formation of an integral lasting lip such as the lip 184 in the shank and forepart of the sole to which a lasted shoe upper may be secured, as by means of staples or the like, and thus held in place during 70 75 80 85 90 95 100

the setting of cement employed for securing the upper to the feather of the insole.

Having described my invention, what I claim as new and desire to secure by Letters Patent of 5 the United States is:

1. That improvement in methods of making reinforced insoles which consists in cutting out an insole, cutting out a reinforcing member for the shank portion of the insole, forming in one of 10 said parts two apertures spaced lengthwise of that part, inserting the opposite end portions of a shank stiffener in said apertures, molding said insole and said reinforcing piece to impart there-to longitudinal and transverse curvatures 15 corresponding to the longitudinal and transverse curvatures of the bottom of a last for a shoe in which the insole is to be incorporated, and securing said insole and said reinforcing piece together with the body portion of the shank stiffener interposed 20 between them.

2. That improvement in methods of making reinforced insoles which consists in cutting out an insole, cutting out a reinforcing member having an outline corresponding to that in the heel and 25 shank portions of the insole, forming two apertures in the reinforcing member spaced apart lengthwise of said member, applying a coating of adhesive to at least one of said parts, assembling 30 a shank stiffener with the reinforcing member by inserting the end portions of the stiffener through said apertures, molding the insole and the reinforcing member to arch them transversely, and utilizing the molding pressure to secure 35 said parts together with the body portion of the shank stiffener interposed between them.

3. That improvement in methods of making reinforced insoles which consists in cutting out an insole, cutting out a member for reinforcing the heel and shank portions of the insole and forming 40 apertures in said reinforcing member for receiving the opposite ends of a shank stiffener, applying a coating of adhesive to one side of said reinforcing member and to one side of the heel and shank portion of the insole, inserting the opposite 45 ends of a shank stiffener through the apertures in said reinforcing member, assembling the stiffened reinforcing member and the insole with their coated surfaces in contact, and applying pressure to the assembled parts to secure them 50 together and to mold the shank portions of the reinforcing member and the insole to a desired contour.

4. That improvement in methods of making reinforced insoles which consists in cutting out an insole, cutting out a reinforcing member for the shank portion of the insole, forming in one of said parts two apertures spaced lengthwise of that part, inserting through said apertures the opposite end portions of a shank stiffener having a spur upon the lower side of its rear portion, molding 60 said insole and said reinforcing piece to impart thereto longitudinal and transverse curvatures corresponding to the longitudinal and transverse curvatures of the bottom of a last for a shoe in which the insole is to be incorporated, and by means of the molding pressure securing the insole and the reinforcing piece together with the body portion of the shank stiffener interposed between them and embedding said spur in the material of 65 said reinforcing piece.

5. That improvement in methods of making shank stiffener units which consists in forming two apertures of substantial width in a reinforcing member for the shank portion of an insole in 70 localities spaced apart lengthwise of said mem-

ber, and threading through said apertures, without distorting to any substantial extent the adjacent material of the reinforcing member, portions of a longitudinally arched shank stiffener which extend in the general direction of the length of the stiffener. 5

6. That improvement in methods of making shank stiffener units which consists in threading portions of a longitudinally arched shank stiffener which extend in the general direction of the length of the stiffener through circular apertures arranged in longitudinally spaced relation in a reinforcing member for the shank portion of an insole, and molding the reinforcing member to fit the contour of the bottom of a last. 10

7. A shank stiffener unit comprising a reinforcing member for the heel and shank portions of an insole having two apertures extending therethrough and spaced apart lengthwise of said member, and a shank stiffener having its opposite 20 end portions extending through said apertures in directions lengthwise of said stiffener. 15

8. A shank stiffener unit comprising a longitudinally arched reinforcing member for the shank portion of an insole having two apertures 25 extending therethrough and spaced apart lengthwise of the reinforcing member, and a longitudinally arched shank stiffener maintained in assembled relation to said reinforcing member by having its opposite end portions projecting 30 through said apertures in directions lengthwise of said stiffener.

9. A shank stiffener unit comprising a longitudinally arched heel and shank reinforcing piece having two apertures formed therein and spaced 35 apart longitudinally of said piece, and a longitudinally arched shank stiffener having its opposite end portions extending through said apertures, said stiffener having a pointed prong 40 formed upon its rear portion and held in engagement with said reinforcing piece in position to be subsequently embedded within the latter. 45

10. A shoe bottom unit comprising an insole member, a shank reinforcing member secured to the insole member, one of said members having two apertures spaced apart lengthwise thereof, and a shank stiffener interposed between said members and having its opposite end portions 50 extending through said apertures. 55

11. A shoe bottom unit comprising an insole and a reinforcing member adhesively secured to the shank portion of the insole and having two apertures spaced apart lengthwise thereof, and a shank stiffener located between the reinforcing member and the insole and having opposite 55 end portions confined within said apertures. 60

12. A reinforced insole unit comprising a relatively flexible insole having two apertures spaced apart lengthwise of said insole in its shank portion, a relatively stiff heel and shank reinforcing piece secured to the upper side of the heel and shank portion of the insole, and a shank stiffener interposed between the heel and shank reinforcing piece and the insole and having its opposite 65 end portions extending through said apertures. 65

13. A shoe bottom unit comprising a lipped insole having two apertures spaced apart lengthwise of the shank portion of the insole, a reinforcing member for the heel and shank portions of the insole adhesively secured to the unlined side of the insole, and a shank stiffener having 70 its body portion located between the insole and the reinforcing member and having its opposite end portions extending through said apertures in the insole. 75

14. A reinforced insole unit comprising an insole member and a reinforcing member secured by means of adhesive to the heel and shank portions of the insole member, one of said members having two apertures spaced apart lengthwise thereof, and a shank stiffener located between said members and having its opposite end portions extending through said apertures, said shank stiffener carrying a spur which is embedded in the material of said apertured member.
15. A reinforced insole unit comprising an insole and a reinforcing piece secured by means of adhesive to the heel and shank portions of the insole and having two apertures spaced apart lengthwise thereof, and a shank stiffener strip interposed between the insole and the reinforcing piece and having its opposite end portions extending through said apertures, said shank stiffener carrying a spur which projects into the material of said insole.

ing piece and having its opposite end portions extending through said apertures, said shank stiffener having a spur carried by its rear portion and embedded in said reinforcing piece.

16. A reinforced insole unit comprising an insole having two apertures spaced apart lengthwise of its heel and shank portion, a reinforcing piece secured to the upper side of the heel and shank portion of the insole, and a shank stiffener interposed between the insole and the reinforcing piece and having its opposite end portions extending through said apertures, said shank stiffener carrying a spur which projects into the material of said insole.

JOHN M. WHELTON.
